CONTAMINATION CONTROL STATION

Gerald W. Wolfe, Bristol, Pa., assignor to Air Control,
Inc., Norristown, Pa., a corporation of Pennsylvania

Filed Oct. 1, 1965, Ser. No. 87,272

Term of patent 14 years

(Cl. D16—2)

Fig. 3

Fig. 2

FIGURE 1 is a perspective view of the front, and one side of a contamination control station showing my new design.

FIGURE 2 is a side elevational view of the unit shown in FIGURE 1, the opposite side being identical to that shown in FIGURE 1; and

FIGURE 3 is a right sectional view taken through the unit of FIGURE 1.

The dominant features of my design reside in the portion shown in full lines. The back of the cabinet is flat and unadorned.

I claim:

The ornamental design for a contamination control station, as shown and described.
